UNITED STATES PATENT OFFICE.

JOHN B. HADAWAY, OF SWAMPSCOTT, AND THOMAS H. SEELY, OF MALDEN, MASSACHUSETTS, ASSIGNORS TO UNITED SHOE MACHINERY CORPORATION, OF PATERSON, NEW JERSEY, A CORPORATION OF NEW JERSEY.

STRETCHING-MACHINE.

1,387,430.

Specification of Letters Patent.

Patented Aug. 9, 1921.

Application filed March 5, 1918. Serial No. 220,495.

To all whom it may concern:

Be it known that we, JOHN B. HADAWAY and THOMAS H. SEELY, citizens of the United States, and residents of Swampscott, in the county of Essex, and Malden, in the county of Middlesex and State of Massachusetts, respectively, have invented certain Improvements in Stretching-Machines, of which the following description, in connection with the accompanying drawings, is a specification, like reference characters on the drawings indicating like parts in the several figures.

This invention relates to machines for stretching various materials, and particularly to those by which a definite form is to be imparted to the material in connection with the stretching operation.

In the production of such articles as leggings from sheets of leather or the like, it may be difficult in a single operation to bring the material, especially when it is thick and firm in texture, to the form sought, and in this event it may be desirable to effect a preliminary shaping of portions, for example the enlargement at the calf of the leg. For this purpose the machine of the present invention is well adapted.

As a feature of the invention, we provide a work-engaging member, preferably a form which is similar to a portion of the surface over which the material operated upon is to fit, and coöperating means, as gripping members, engaging the material at each side of the form for successively applying tension to said material under the control of the machine to stretch it upon the form, and thus gradually and without undue strain expand the portion under treatment to the shape sought.

The above-mentioned tension is obtained by relative movement of the work-engaging members, as the form and gripping means, in the organization illustrated the form being thus moved by the application of power.

Another feature of the invention consists in utilizing said relative movement to cause one of the members to engage the material and thereafter to effect engagement of another member. In the preferred embodiment of the invention, an operating member in its travel first closes a set of grippers at

one side of the form, then closes an opposite set and finally moves the form against the work to produce the stretching and forming action. This sequential engagement of the material enables the operator to position the work conveniently.

A further feature provides means under control of the operator for causing, prior to the stretching movement under power operation, an initial engagement of the material and form, preferably by a preliminary adjustment of the form toward the stretching position. This may be through the agency of a manually operable adjusting member, conveniently inclined or wedge-shaped. By this means the operator, after the work has been gripped, may bring the form into such contact with it that the stretching under the influence of power shall begin with substantially the same initial tension for every operation.

To retain this manual adjustment against accidental change during the stretching operation, we provide, as still another feature of the invention, a locking means for the adjusting member and, as herein described, there is also furnished automatic means for actuating the locking means at predetermined times. This automatic control may be effected by connection with the power-operated means, which preferably both secures and frees the manually operable adjusting member.

To avoid excessive strain upon the material, the invention includes as an additional feature, automatic means for controlling the action of the stretching instrumentalities. In accordance with the present disclosure, the material is stretched against the tension of yieldable engaging members, and the extent of this yield, this decreasing as the material expands under the stretching force, is utilized to release said material from the gripping devices through the agency of the driving or power mechanism. To this end, and as an auxiliary feature, the gripping devices are mounted upon opposite sides of an intermediate material-engaging member to move together and have yieldable and preferably adjustable means to resist their movement.

Another feature is found in automatic means for stopping the operation of our improved machine at one or more predetermined intermediate points in a cycle provided for by the operating mechanism. This means we have shown as consisting of an actuating connection between the operating means for the material-engaging members and the driving means through which power is applied to the machine. This connection, as the operating means travels, produces a disconnection of the driving mechanism.

With the form and stretching means, especially for legging work when the form corresponds in contour to a portion of a leg, we may employ a mold so coöperating with the form that the stretched material is pressed between them, preferably yieldably. One of these coöperating elements may be heated, the form being here provided with sources of heat of different capacity arranged to best distribute the effect.

The accompanying drawings illustrate a particular embodiment of the invention,

25 Fig. 1 being a full side elevation of the machine;

Fig. 2 a partial enlarged horizontal section on the line 2—2 of Fig. 1;

30 Fig. 3 an enlarged rear elevation of the upper portion of the machine;

Fig. 4 an enlarged front elevation of the same portion, parts being broken away;

Fig. 5 a vertical section on the line 5—5 of Fig. 3; and

35 Fig. 6 a perspective view of a portion of the driving and controlling mechanism.

A main supporting frame is made up of side frames 10, 10 joined by a cross bar 12 (Fig. 6), and vertical rods 14 extended 40 through openings in the side frames and connected by a lower cross bar 16 and an upper tie bar 18. The side frames are each shown as extended by horizontal bars 20 lying just inside the rods 14 and supported 45 at their front and rear extremities by vertical bars 22 and 24, respectively, bolted to the side frames. The main frame carries work-engaging members, here illustrated as provided by opposite gripping devices 26, 26 50 of which there are preferably a plurality of sets, and an intermediate form 28. The gripping devices are shown as supported in opposite pairs on pivoted frames each of which furnishes a parallel movement.

55 These frames may consist of opposite pairs of vertical bars 30, 30 joined at their upper extremities by pairs of cross links 32, 32 through pivot pins 34, the lower ends of the bars 30 being articulated to generally horizontal arms 36 of bell-crank levers 38 pivoted at 40 upon rods carried by the bars 20 of the main frame. The lower member of each parallel movement is furnished by links 42 pivoted to generally vertical arms 60 44 of the levers 38. The arm 44 on each

of the rear bell-crank levers has an extension, to which is attached a spring 46 secured at its opposite extremity to a screw 48 passing through one of a series of openings in a bar 50 connecting the members 20 70 and 24 at opposite sides of the frame. Upon the outer ends of the screws 48 are adjusting nuts 52 provided with hand wheels by which the nuts may be turned to move the screws and thus separately adjust the tension of each spring 46. The springs normally hold the frames supporting the gripping devices in the position peculiarly illustrated in Figs. 1 and 5 of the drawings, the movement of the frames being limited by a 80 bar 54 extending through slots 56 in the rear frame bars 30 and contacting with the top of the main frame bars 20. The slots are sufficiently long vertically to allow an upward movement of the pairs of frame 85 members 30 independently of one another, though they are all held in the same normal position. Secured in pairs near the opposite extremities of the upper frame links 32 are fixed jaws 58 of the gripping devices, with which coöperate movable jaws 60 pivoted upon the pins 34 of the supporting frame. The coöperating faces of the fixed and movable jaws are preferably roughened to enable them to better grasp the material to be operated upon. From each jaw 60 an arm 62 extends downwardly and outwardly, and has at its lower end a generally horizontal recess to receive a cylindrical plunger 64, which carries outside the arm, rotatable upon a pin 66, a pair of rolls 68 for contact with an operating member to be later described. The weight of the jaw arms 62 is sufficient to maintain the jaws normally open, they being limited in their movement in this direction by the contact of the pins 66 with the frame bars 30. Within the recess at the rear of each plunger is a spring 70 tending to force said plunger and supported roll outwardly against a limiting pin 72 situated in a bore in the arm 62. A screw 74 is threaded through each arm at the end of the recess and serves to vary the tension of the corresponding spring 70.

Mounted upon the rods 14 of the main frame are guide sleeves 76, 76 fixed in position by set screws, and upon which travels a supporting member having a main horizontal portion 78 and guide projections 80, the outer faces of which are curved to embrace the sleeves 76. At the under side of the support is a series of depending arms 82, preferably integral with the portion 78, with which arms contact pins 84 set in the bars 32 guiding the frames supporting the gripping devices in their vertical movement. Certain of the depending arms, two designated as 86 being here shown, are longer than the companion arms for a purpose which will later appear. On the sup-

port 78 is mounted the intermediate work-engaging member 28, in the present instance consisting of a form, the upper part 88 of which is similar in contour to the rear of 5 the calf portion of a leg. The ends of the form have guide portions 90 curved to fit the sleeves 76 and permitting the form to move vertically above its support. The form may be heated by devices within it, 10 as electric units, of which two, 92 and 94, are shown. The unit 92 is located in the calf portion of the form and is of greater heating capacity than 94, which is in the contracted portion of the form. This arrangement not only better distributes the 15 heat with respect to the magnitude of the mass of metal, but also applies more where a greater curvature of the material to be formed is desired, so that more shrinking 20 effect is obtained. This is particularly useful in connection with leather.

Above and in alignment with the form, we have a mold 97 which is hollowed out to receive the upper portion of the form. This 25 mold is carried upon rods 99 extending through a series of openings in the tie bar 18. The lower ends of the rods 99 are threaded to receive nuts 101 and between these nuts and the bar 18 are helical springs 30 103. Nuts and check nuts 105 upon the threaded upper ends of the rods retain the mold in its normal vertical position. The tension of the springs 103 may be adjusted by turning the nuts 101. The mold is preferably unheated, the application of a cold 35 surface to the opposite side of the material from that which is heated by the form causing a greater shrinking action. The inverted position of the mold, its hollow side 40 being down, prevents the accumulation of dirt in the depression.

The support 78 and form 28 may be moved vertically away from the gripping devices 26 by operating mechanism including a head 45 having separate sections 96 and 98, these being in the form of heavy bars extending between and guided by the frame rods 14. The lower section 96 is connected at 100 to the upper end of a toggle 102, the opposite 50 extremity of which is pivoted at 104 upon the lower frame bar 16. The central articulated portion of the toggle is oscillated through the contact of a roll 107 rotatably mounted on a link 106 pivoted to the toggle, 55 with a cam 108 carried by a countershaft 110 journaled in the side frames 10. The link 106 is conveniently guided by a fork 112 which may be integral with it and embraces the shaft 110. This shaft and the cam are 60 rotated to straighten and break the toggle and thereby raise and lower the head section 96, through a gear 114 which meshes with a pinion 116 upon a main shaft 118 mounted in bearings in the lower portion of the side 65 frames 10 and rotatable from any conven-

ient source of power by a pulley 120 joined to the shaft 118 through a clutch 122. The clutch may be of any convenient type providing for continuous rotation of the driven element from the driving element when a 70 member, as a treadle 124 mounted upon a cross rod 125, is actuated by the operator. A brake 126 is associated with the clutch to promptly stop the rotation of the driven parts when the clutch is released. 75

The upper section 98 of the head rests upon the operating section 96 by gravity and is preferably saddle-shaped transversely, having opposite series of lateral projections 128 between which the bars 30 pass and are 80 supported against tipping transversely of the frame. The rear and front projections 128 have, respectively, upper inclined actuating faces 130 and 132 occupying different vertical positions and operating upon the 85 rolls 68, 68 of the corresponding sets of gripping devices. As a result of this arrangement, as the head section 98 is raised the faces 130 first contact with the rolls of the rear gripping devices closing the jaws, 90 and then the faces 132 striking the rolls of the opposite set of jaws close them. After the rolls leave the inclined actuating faces, they ride upon vertical retaining faces 134 which temporarily maintain the engagement 95 of the jaws with the material which has been inserted between them. After the operation of the last-mentioned gripping devices, the upper horizontal face of the lower head section 96 contacts with the support projections 86, these extending through aligned openings 136 in the head section 98 (Fig. 4) and raises the form away from the gripping devices. The material, which when supplied to the machine for engagement by the 100 gripping devices is placed across the form, 105 is thus stretched by this movement.

In addition to the raising of the form by the power-operated means, it is also capable of manual adjustment. For this purpose, 110 there is interposed between the support 78 and the form an adjusting member 138 mounted to slide between the guide plates 140 secured to the sides of the form, said member preferably having two inclined surfaces which may each be provided with a series of steps 142 (Figs. 3 and 4). These contact in the longitudinal movement of the adjusting member with projections 144 upon the under side of the form. To move the 115 adjusting member, there is connected to it by a pivoted link 148 a lever 146 fulcrumed upon one of the sleeves 76. The material to be operated upon having been placed upon the form and grasped by the gripping 120 devices 26, the operator may thrust the wedge member inward beneath the form by means of the lever, and as the steps of the incline contact with the projections 144 they 125 gradually raise the form, rounded corners 130

of the steps permitting the wedges to readily slip beneath the projections. This continues until the form is brought into sufficiently close engagement with the material, so that the work may be always under substantially the same initial tension when power is applied to stretch it.

To secure the member 138 in the position to which it is adjusted, a locking member 150 (Figs. 2, 4 and 5) is movably mounted adjacent to the adjusting member, the two elements having a coöperating projection and series of depressions. As shown, a projection 152 (Fig. 2) is carried by the member 138, depressions 154 being formed in the side of the locking member 150 toward the projection. These depressions correspond in number to the steps of each of the inclines, so that the member 138 may be secured in whatever position it may be adjusted. The locking member 150 is in the form of a bar upon the under side of which are lugs 155 secured to a spindle 156 having a bearing in brackets 158 projecting from the support 78. Surrounding the spindle, near its outer end beyond the outer bracket, is a member 160 provided with opposite arms and being frictionally held between a sleeve 162, flanged at its end and secured against rotation upon the outer bracket, and a washer 164 which is forced toward the member 160 by a helical spring 166 situated between it and a nut and check nut 168. Upon each side of the member 160, between the sleeve and the washer, are placed disks 169 of some suitable friction material, such as leather, and the spring 166 is placed under such tension by the nuts that the spindle 156 may be caused to turn by the member 160, though these elements are free to slip relatively to one another when the locking member reaches the end of its movement. The outer arm of the member 160, or that toward the front of the machine, carries a pin 170 extending into a slot in a link 172 pivoted to the section 98 of the operating head. The opposite or inner arm has a pin 176 entering a slot in a link 178 pivoted at the end of the tie bar 18. When the parts are in their normal position, or at the beginning of an operation, the link 172 is so drawn down by the head section 98 that the pin 170 contacts with the end of its slot, thus turning the spindle and moving the depressions 154 clear of the pin 152 in the adjusting member. When the form rises to stretch the material, the pin 176 moving with it contacts with the upper extremity of the slot in the link 178. This rotates the spindle in a clockwise direction as seen in Fig. 1, bringing the depression in the locking member, which may be at that time opposite the pin 152, into engagement therewith, thus retaining the adjusting member against accidental displacement. Opposite movement of the form at

the end of the operation rotates the spindle in an anti-clockwise direction and releases the adjusting member, as already described. The frictional connection of the member 160 to the spindle allows a movement of the links 172 and 178 with respect to their pins beyond that which is necessary to rotate the spindle, without interfering with the operation of the elements.

After the operating head has by its surfaces 130 and 132 caused the jaws to grip the work, the section 98 is held at a definite minimum operating height to retain the jaws closed by contact of the surfaces 134 with the rolls 68, while the section 96 is successively raised by the driving mechanism, carrying the section 98, the support 138 and the form above this minimum height to perform the stretching operation. For the purpose of thus retaining the section 98 in this jaw-actuating position, there is connected to it at its ends outside the frame rods 14 opposite links 180, the lower ends of which are attached to a bar 182 arranged to slide upon the rods 14 (Figs. 1 and 6). Secured to or integral with the outer or front side of this bar 182 is a latch member 184 coöperating with a latch projection or shoulder 186 upon an arm 188 mounted to turn about the treadle rod 125 and held between the treadle and a collar 189 fixed upon the rod. A spring 190, joined to the arm 188 and to the rear portion of the main frame, acts to hold the inner face of the projection 186 against the latching member 184. As the head section 98 is raised by the lower section 96, it carries the bar 182 with it. When, by the operation of the surfaces 132, the front set of gripping devices has been closed, the lower edge of the member 184 reaches a point just above the shoulder 186, at which time the spring 190 draws the shoulder beneath the member thus latching up the bar 182 and the section 98 from which it is hung.

After the head section 98 has been thus latched in the work-engaging position, the operation continues by successive reciprocations of the form until the desired amount of stretch has been imparted to the material under treatment, at which time it is desired to release the section 98, this, in its descent by gravity, in turn releasing the gripping devices. Depending from an extension of one of the frame bars 30 supporting the grippers is a link 192 situated above and just at the rear of the arm 188. Pivoted connected to the lower end of this link is a second link 194, through a slot in the other extremity of which extends a pin 196 carried by the toggle members near their juncture. Fixed at the bottom of the link 192 is a contact portion 198, which in the normal position of the gripper frame comes into horizontal alinement with a coöperating

contact portion 200 upon the upper end of the arm 188. As the form is raised by the toggle to stretch the material, a pull is exerted on the gripping devices tending to raise them with their frames against the tension of the springs 46. The extent of the upward movement of a frame depends, in addition to the amount of resistance of the spring 46 due to its construction and adjustment, upon the elasticity of the material under treatment. At the beginning of the stretching operation the material resists the movement of the form, so that the gripping devices and the supporting frames may be raised considerably. This, at the time the toggle is straightened, brings the contact portion at 198 above the portion 200, so that when the toggle pin 196 contacts with the outer or forward end of the slot in the link 194 to move the first-named contact portion toward the second they are out of horizontal alignment and the portion 200 is not struck. As the material expands under the stretching operation, less and less tension is exerted upon the spring 46, allowing the gripper frame to remain at a lower position. Finally when the desired amount of stretch has been imparted to the material, this being determined by the adjustment of the nuts 52, the contact portion 198, upon the straightening of the toggle, will be moved against the portion 200. This swings the arm 188 toward the front of the machine, removing the shoulder 186 from beneath the latch member 184. The bar 182 thus released falls, and with it the head section 98, until stopped by the lower section. Both the retaining faces 184 and operating faces 130 and 132 of the section 98 are thus carried below the rolls 68, permitting the arms 62 to swing inwardly to open the gripping jaws and release the material. This release notifies the operator that the machine has acted to the desired degree and he may stop it by removing his foot from the treadle 124.

On account of considerable tension exerted by the spring 190 and the relatively short releasing movement of the contact portions 198 and 200, in absence of special provision to prevent it the latching element 184 might not fall from the shoulder 186 before the arm 188, released by the withdrawal of the contact portion 198 upon the breaking of the toggle, would be drawn back to the latching position and so continue to hold up the bar 182 and the head section 98. To prevent this and insure the releasing of the work from the gripping devices at the desired time, means is preferably provided to positively prevent such reengagement. Pivoted near the upper end of the arm 188 is a stop member 202, the end of which projects over the inner or rear face of the arm 188 into the space occupied by the member 184 when the head section 98 is latched up. This position

of the stop member is normally maintained by a spring 206 extending from the member to the arm 188 and drawing the former against a pin 204. As the member 184 rises prior to engagement with the shoulder 186, its upper edge strikes the overhanging extremity of the stop member 202, moving this member before it about its pivot, so that the latching engagement is not interfered with. When, however, the contact portion 198 thrusts the shoulder 186 from beneath the coöperating member, the stop member is promptly drawn by its spring into the path of the member 184, so that the arm 188 is held by the engagement of the end of the stop member with the forward face of the member 184 from returning to the latching position until the adjacent vertical faces of the members 186 and 188 have come into contact to nullify the latching effect.

While the driving mechanism acting through the clutch tends to cause the operating head to move the work-engaging members through a continuous cycle of operations—including the closure of one set of grippers, followed by the closure of the opposite set of grippers with a final succession of stretching movements of the form until released under the control of the work, as above described—for the proper manipulation of the work, we prefer to automatically interrupt this cycle at certain intermediate points controlled by the operating mechanism. The treadle 124, by which the operator causes the engagement of the clutch 120, is free to turn about the rod 125 and has pivoted upon an upward extension 208 (Figs. 1 and 6) a hooked connecting member 210, the end 212 of which overhangs a pin 214 upon an arm 216 also capable of turning about the treadle rod. Pivoted connecting this arm 216 and the clutch mechanism is a link 218. A spring 220, connecting the treadle and frame, holds the former in its normally raised position. Above the hooked portion 212 of the member 210 is a horizontally-extending pin 222 engaged by the hooked extremity 224 of a disengaging member in the form of a bar 226, movable through an opening in a guide stud 228 carried at the inner side of one of the frame members 10. A spring 230 joins the member 210 and the bar 226 to retain the hook 224 in engagement with the pin 222. Upon the bar 226, near the member 182 movable with the head section 98, are two contact projections 232 and 234 separated from one another by a space approximately equal to the distance through which the operating head moves to effect the closure of the second set of gripping devices after the actuation of the first set. These projections lie just inside, but normally out of engagement with, a contact member 236 fixed to the ends of lugs 238 formed on the forward face of the bar 182, 130

the upper edge of this contact member being somewhat below the lower projection 232. When the operator depresses the treadle, swinging the extension 208 forward, the 5 hook 212, by its engagement with the pin 214, draws the link 218 forward to cause the engagement of the clutch. This brings the operating mechanism into action to straighten the toggle and raise the operating 10 head. With the member 210 the lower end of the bar 226 also swings forward, bringing the projection 232 above the member 236. Now, as the head rises, and with it the bar 182 and contact member 236, the latter 15 strikes the under side of the projection 232 lifting the bar and drawing the hook 212 away from the pin 214. This releases the clutch from the treadle and stops the movement of the operating mechanism. The 20 head section 98 is consequently stopped in its position for closing the rear set of gripping devices. This gives the operator an opportunity to position the work for engagement by the forward set. When he raises 25 his foot from the treadle the projection 232 is moved back from the member 236 and the bar falls, allowing the hook 212 to reengage the pin 214. A second depression of the treadle moves the projection 234 above the 30 member 236 and again operates the clutch, the disengagement of which is effected by contact between the member 236 and the projection 234 in the manner just explained, when the head section 98 reaches the height 35 at which the forward set of gripping devices is closed. Upon the succeeding release of the treadle both projections 232 and 234 move below the member 236. Thereafter upon the actuation of the treadle, the driving 40 mechanism acting through the clutch continues to reciprocate the form to stretch the material as long as the treadle is held down.

In using our improved machine for the 45 stretching of leggings preliminarily to their final forming, the operator lays a suitably tempered blank across the top of the form with one edge between the jaws of the rear set of gripping devices 26 and actuates the 50 treadle. The clutch connects the driving mechanism and operating mechanism, straightening the toggle and raising the operating head until the surfaces 130 cause the 55 jaws of the rear set of devices 26 to grip the material. At this time, the contact member 236 reaches the disengaging projection 232 to throw off the connections between the treadle and clutch and free the operating mechanism from the driving mechanism. 60 The head therefore stops with the jaws held closed by the surfaces 134. A succeeding actuation of the treadle closes the forward set of gripping jaws through the agency of the surfaces 132, and the clutch is again 65 thrown off by the contact of the member 236

with the upper projection 234. Now both sets of jaws are held upon the work by the head surfaces 134, the head at this time being latched up in this grip-retaining position by the engagement of the latching elements 70 184 and 186. Thereupon the operator draws out the lever 146, until the adjusting member 138 raises the form into such engagement with the material that it is ready for the immediate exertion of the stretching effect 75 upon further relative movement of the parts. Now the operator presses down the treadle and retains it there. The operating head is successively reciprocated by the driving mechanism, coming into contact with the 80 projections 86 of the form support and forcing the form against the material held between the jaws to stretch it. As the form approaches its limit of upward movement, it enters the depression in the mold 97 which 85 yieldingly presses upon the material, tending to set it in the form to which it is stretched, this being aided by the shrinking action of the inner heated form and the outer cold mold. During this reciprocation 90 the surfaces 134 move beneath the rolls 68 of the gripping devices to hold the jaws closed. At the beginning of the movement of the form under power operation, the pin 176 of the locking device for the adjusting 95 member 138 strikes the end of the slot in the link 178 to so shift the locking device that the member is held in place during the power operation. As the stretching action continues and the material expands, the gripping devices and their supporting frames rise less against the pull of the springs 46, until, when the tension of the latter is sufficient to hold them in their lowest or normal position, the contact members 198 and 200 100 come together to disengage the latching members and release the operating head. 105 This falls, carrying the surfaces 134 away from the rolls 68, thus freeing the work and stopping the stretching action. A signal is 110 thereby furnished the operator of the completion of the stretching operation, and he thereupon frees the treadle and the machine is ready to receive another blank. The adjusting member 138 is freed from the locking device by the contact of the pin 170 with the upper extremity of the slot in link 172.

Having thus described our invention, what we claim as new and desire to secure by Letters Patent of the United States is:

1. In a machine of the class described, a form for co-operation with the material to be operated upon, and means operating successively under the control of the machine 125 for placing the material under tension to stretch it across the form.
2. In a machine of the class described, a form for co-operation with the material to be operated upon, material-engaging means, 130

- a source of power for causing relative movement of the form and engaging means, and means for controlling the application of power, said controlling means being constructed and arranged to cause for a single actuation a plurality of relative movements of the form and engaging means.
3. In a machine of the class described, a form for coöperation with the material to be operated upon, material-engaging means, and means for successively reciprocating the form with respect to the engaging means.
4. In a machine of the class described, means for gripping opposite edges of the material to be operated upon, a member contacting with an intermediate portion of the material, and means operating successively under the control of the machine for moving the members relatively to one another to gradually stretch the material.
5. In a machine of the class described, members for gripping opposite edges of the material to be operated upon, a member contacting with an intermediate portion of the material, and automatic means for successively moving the members relatively to one another to gradually stretch the material.
6. In a machine of the class described, a form for coöperation with the material to be operated upon, means operating successively under the control of the machine for placing the material under tension to stretch it across the form, and yieldable connections for the tension-applying means, said connections being tensioned during the stretching operation.
7. In a machine of the class described, a form for coöperation with the material to be operated upon, means operating successively under the control of the machine for placing the material under tension to stretch it across the form, and yieldable connections for the tension-applying means, said connections being differently and progressively tensioned during the successive operations.
8. In a machine for forming leggings, a form corresponding in contour to a portion of the leg for coöperation with legging material, material-engaging means, a source of power for causing relative movement of the form and material engaging means, said means engaging the material at closely adjacent points throughout substantially its entire length to stretch said material over the form and impart to it a leg-shape, and yieldable means for resisting said movement.
9. In a machine of the class described, a plurality of separate material-engaging means, an intermediate material-engaging means, means relatively movable to stretch the work, and means acting during a portion of the movement for operating one of the first-mentioned engaging means and thereafter acting to operate the opposite engaging means.
10. In a machine of the class described, a plurality of separate material-engaging means, an intermediate material-engaging means, and a movable member, said member during a portion of its movement operating one of the first-mentioned engaging means and then upon further movement operating the opposite engaging means.
11. In a machine of the class described, a plurality of separate material-engaging means, an intermediate material-engaging means, and a movable member, said member during a portion of its movement operating one of the first-mentioned engaging means, then upon further movement operating the opposite engaging means, and finally operating to move the intermediate engaging means.
12. In a machine of the class described, a plurality of devices for gripping the work, and a movable member, said member during a portion of its movement operating a gripping device and during its further movement operating another gripping device.
13. In a machine of the class described, a plurality of devices for gripping the work, and a movable member having contact faces normally situated at different distances from the gripping devices and successively co-operating with them to cause them to engage the work at different times.
14. In a stretching machine, a form, a plurality of gripping devices coöperating with the work in the stretching operation, and a movable member for successively operating the gripping devices and form.
15. In a stretching machine, a form, a plurality of gripping devices coöperating with the work in the stretching operation, and a movable member for successively operating the gripping devices and form, the operation of the form occurring a plurality of times for each operation of the gripping devices.
16. In a stretching machine, a form, a plurality of gripping devices coöperating with the work in the stretching operation, and a movable member coöperating first with the gripping device to close it, then on further movement acting to close another gripping device, and finally coöperating with the form to force it against the work.
17. In a stretching machine, a form, a plurality of gripping devices coöperating with the work in the stretching operation, and a movable member coöperating first with a gripping device to close it, then on further movement acting to close another gripping device, and finally coöperating with the form to force it against the work a plurality of times before again acting on the gripping devices.
18. In a machine of the class described, a reciprocatory head, work-engaging members between which the head moves and

- with which it coöperates to effect engagement, and a work-engaging member situated in the path of the head though initially out of coöperation therewith to be moved 5 by said head.
19. In a machine of the class described, a reciprocatory head having oppositely inclined surfaces, separate grippers each provided with a movable jaw member coöperating with one of the inclined surfaces, and a movable form and form support, the support contacting with the head between the inclined surfaces. 10
20. In a stretching machine, a form, means for engaging the material to be stretched upon opposite sides of the form, power-operated means for moving the form toward stretching position, and manually operated means constructed and arranged to 15 independently move the form.
21. In a stretching machine, a form, means for engaging the material to be stretched upon opposite sides of the form, and power-operated means for effecting a preliminary movement of the engaging means in the stretching operation, said means thereafter being effective to successively reciprocate the form under the control of the machine to accomplish gradually the 25 stretching operation.
22. In a stretching machine, material-engaging members, a form support, a form for coöperation with the engaging members movable upon the support, and an adjusting 30 member interposed between the support and form, said form and the adjusting member having contacting surfaces one of which is inclined.
23. In a stretching machine, material-engaging members, a form support, a form 35 for coöperation with the engaging members movable upon the support, and an adjusting member interposed between the support and form, said form and adjusting member having contacting surfaces one of which is inclined and provided with steps.
24. In a stretching machine, material-engaging members, a form support, a form movable upon the support, an adjusting 40 member interposed between the support and form, a lever, and connections between the lever and adjusting member.
25. In a stretching machine, work-engaging means, power-operated means for moving the work-engaging means, manually operated means for moving the work-engaging means, and automatic means for locking the moving means at predetermined times. 45
26. In a stretching machine, work-engaging means, power-operated means for moving the work-engaging means, manually operated means for moving the work-engaging means, and means controlled by the power-operated means to retain the work-engaging 50 means in its position of manual adjustment.
27. In a stretching machine, work-engaging means, power-operated means for moving the work-engaging means, manually operated means for moving the work-engaging means, and means controlled by the power-operated means to retain the work-engaging means in its position of manual adjustment and thereafter to release said work-engaging means. 70
28. In a stretching machine, a form, power-operated means for moving the form, manually operated means for moving the form, and means controlled by the power-operated means to lock the manually operated means against movement. 75
29. In a stretching machine, a form, power-operated means for moving the form, manually operated means for moving the form, means controlled by the power-operated means to lock the manually operated means against movement, and means also controlled by the power-operated means to free the manually operated means. 80
30. The combination with a movable support, of a form movable on the support, a form-adjusting member, and locking means for the adjusting member controlled in the movement of the support. 90
31. The combination with a reciprocating support, of a form movable on the support, a form-adjusting member, and locking means for the adjusting member oppositely controlled in the reciprocation of the support. 95
32. In a stretching machine, work-engaging members relatively movable toward and from one another, independent means constructed and arranged to effect the relative movement, and means under the influence of one of said moving means for controlling the other. 100
33. In a stretching machine, work-engaging members and a supporting member relatively movable toward and from one another, a form carried by the supporting member, an adjusting member for varying the position of the form on the support, and locking means for the adjusting member made effective in one relative movement of the engaging members and support and ineffective in the opposite movement. 105
34. In a stretching machine, work-engaging members and a supporting member relatively movable toward and from one another, a form carried by the supporting member, an adjusting member for varying the position of the form on the support, and locking means for the adjusting member made effective when the engaging members and support separate and ineffective when they approach. 110
35. The combination with a support and a form movable thereon, of a form-adjusting member, and a locking member movable into and out of coöperation with the adjusting member, said adjusting member 115
- 120
- 125
- 130

- and locking member being provided with a coöperating projection and series of depressions.
36. In a stretching machine, a form, power-operated means for moving the form, manually operated means for moving the form, and means controlled by the power-operated means and including frictional connections to retain the form in its position of manual adjustment. 10
37. The combination with a movable support, of a form movable on the support, a form-adjusting member, locking means for the adjusting member, and actuating means for the locking means joined to a point movable relatively to the locking means and including frictional connections. 15
38. In a stretching machine, a movable support, a form adjustable in position on the support, and means for retaining the form in its adjusted position including an oscillatory spindle provided with locking means, and a slotted connection between the spindle and a relatively movable point organized to cause rotation of the spindle and also to permit its bodily movement. 20
39. In a stretching machine, a frame, a support movable thereon, a form adjustable in position on the support, means for retaining the form in its adjusted position and including an oscillatory spindle provided with locking means, and a slotted connection between the spindle and frame. 25
40. In a stretching machine, a frame, a support movable thereon, a form adjustable in position on the support, means for retaining the form in its adjusted position and including an oscillatory spindle provided with locking means, an arm frictionally connected to the spindle, and a link pivoted to the frame and having a shifting pin-and-slot connection with the arm. 30
41. In a stretching machine, a reciprocating operating member, a support movable relatively thereto, a form adjustable in position on the support, means for retaining the form in its adjusted position including an oscillatory spindle provided with locking means, and a slotted connection between the spindle and operating member. 35
42. In a machine of the class described, means for stretching material, and automatic means for controlling the action of the stretching means in accordance with the amount the material has been stretched. 40
43. In a machine of the class described, means for stretching material, and means dependent upon the amount the material has been stretched for notifying the operator of the degree of action of the machine. 45
44. In a machine of the class described, means for gripping and stretching material, and automatic means depending on the amount the material has been stretched for releasing the gripping means. 50
45. In a machine of the class described, means for stretching material, driving mechanism therefor, and means operable from the driving mechanism for limiting the action of the stretching means. 55
46. In a machine of the class described, means for stretching material, driving mechanism therefor, and means operable from the driving mechanism and controlled by the stretching means for limiting the action of said stretching means. 60
47. In a machine of the class described, yieldable means for gripping and stretching material, and automatic means depending upon the amount of yield for releasing the gripping means. 65
48. In a stretching machine, traveling and yieldable stretching members, and means for controlling a traveling member through the movement of a yieldable member. 70
49. In a machine of the class described, a plurality of movable work-engaging means, an operating member movable to different positions to effect the movement of the work-engaging means, and means for retaining the operating member against recession from one of its operating positions while permitting it to advance to another operating position. 75
50. In a machine of the class described, a plurality of movable work-engaging means, an operating member for the work-engaging means having independently movable sections, and means for retaining one of the sections in its operating position for one 80 of the work-engaging means while permitting the movement of the other section. 85
51. In a machine of the class described, a plurality of movable work-engaging means, an operating member for the work-engaging means having independently movable sections, means for reciprocating one of the sections, and means for locking the other section against movement in one direction. 90
52. In a stretching machine, the combination with a movable form and yieldable work grippers, of operating means for moving the form and closing the grippers, means for retaining the operating means in its 95 gripper-closing position, and means controlled by the yield of the grippers for releasing the operating means. 100
53. In a machine of the class described, a plurality of movable work-engaging means, an operating member movable to different positions to effect the movement of the work-engaging means, means for retaining the operating member against recession from one of its operating positions while 105 permitting it to advance to another operating position, and automatic means for freeing the operating member. 110
54. In a machine of the class described, a plurality of movable work-engaging 115

means, an operating member movable to different positions to effect the movement of the work-engaging means, means for retaining the operating member against recession 5 from one of its operating positions while permitting it to advance to another operating position, means for freeing the operating member, and connections to a work-engaging member for controlling the freeing 10 means.

55. In a machine of the class described, a plurality of movable work-engaging means, an operating member movable to different positions to effect the movement of the 15 work-engaging means, means for retaining the operating member against recession from one of its operating positions while permitting it to advance to another operating position, power-operated means for freeing the 20 operating member, and connections to the work-engaging means for positioning the freeing means.

56. In a machine of the class described, work-engaging means, a movable operating 25 member therefor, retaining means for the operating member, means for disengaging the retaining means, and means for preventing reengagement of the operating means and retaining means.

57. In a machine of the class described, work-engaging means, a movable operating member therefor, retaining means for the operating member including contacting latch 30 members, means for disengaging the latch members, and a stop movable into the path 35 of one of the members.

58. In a machine of the class described, work-engaging means, a movable operating member therefor, retaining means for the 40 operating member including contacting latch members, a spring tending to hold the latch members in engagement, means for disengaging the latch members, and a stop movable into the path of one of the members 45 to prevent reengagement under the influence of the spring.

59. In a machine of the class described, work-engaging means, a movable operating member therefor, retaining means for the 50 operating member including contacting latch members, means for disengaging the latch members, and a stop carried by one of the members and movable into the path of the other member.

60. In a machine of the class described, work-engaging means, a movable operating member therefor, retaining means for the operating member including co-operating latching surfaces movable into engagement 60 in two directions, means for separating the surfaces, and means for preventing their reengagement in one direction while permitting movement in the other direction.

61. In a machine of the class described, 65 movable work-engaging means, a reciproca-

tory head for effecting the movement, a latch member connected to the head, a member fixed relatively to the head, and a latch member carried by the relatively fixed member and co-operating with the first-named 70 member.

62. In a machine of the class described, movable work-engaging means, a reciprocatory head for effecting the movement, driving mechanism for the head, a latch member 75 connected to the head, a member fixed relatively to the head, a latch member carried by the fixed member and co-operating with the first-named latch member, and a contact member actuated by the driving mechanism 80 to move one of the latch members.

63. In a machine of the class described, movable work-engaging means, a reciprocatory head for effecting the movement, driving mechanism for the head, a latch 85 member connected to the head, a member fixed relatively to the head, a latch member carried by the fixed member and co-operating with the first-named latch member, and a contact member connected to a work-engaging member and actuated by the driving mechanism 90 to move one of the latch members.

64. In a machine of the class described, movable work-engaging means, a reciprocatory head for effecting the movement, a latch member 95 connected to the head, a member fixed relatively to the head, a latch member carried by the fixed member and co-operating with the first-named member, and a stop carried by one latch member and being movable into the path of the other.

65. In a machine of the class described, movable work-engaging means, a reciprocatory head for effecting the movement, said 105 head consisting of independently movable sections one of said sections co-operating with the work-engaging means, driving means connected to the other section, and latch members respectively attached to the section 110 co-operating with the work-engaging means and to a relatively fixed point.

66. In a stretching machine, devices for gripping opposite sides of the material to be stretched, an intermediate material-engaging member, a support upon which the opposite gripping devices are mounted to move together, and yieldable means for resisting the movement of the support. 115

67. In a stretching machine, devices for 120 gripping opposite sides of the material to be stretched, an intermediate material-engaging member, a support upon which the opposite gripping devices are mounted to move together, yieldable means for resisting 125 the movement of the support, and means arranged to vary the resistance.

68. In a stretching machine, a plurality of pairs of devices for gripping opposite sides of the material to be stretched, an interme- 130

diate material-engaging member, an independently movable support upon which each of the pairs of gripping devices is mounted, and independently adjustable means for resisting the movement of each support.

5 69. The combination with a form, of work-gripping members situated at each side of the form, and an articulated frame furnishing a parallel movement and upon which the 10 gripping members are mounted.

70. The combination with a form, of work-gripping jaws situated at each side of the form, and an articulated frame furnishing a parallel movement and upon the articulations 15 of which the jaws are pivoted.

71. The combination with a form, of work-gripping members situated at each side of the form, a frame upon which the gripping members are mounted, and an operating 20 member for the gripping members furnishing guides for the frame.

72. The combination with a form and its support, of work-gripping members situated at each side of the support, and a movable 25 frame upon which the gripping members are mounted, said frame being guided in its movement by the form support.

73. In a stretching machine, a main frame, opposite levers fulcrumed thereon, bars pivoted upon the levers, links connecting the levers and bars and furnishing therewith a supporting frame, and opposite work-engaging jaws mounted upon the supporting frame.

30 74. In a stretching machine, a main frame, opposite bell-crank levers fulcrumed thereon, bars pivoted upon the levers, links connecting the levers and bars and furnishing therewith a supporting frame, opposite work-engaging jaws mounted upon the supporting frame, and springs connecting the levers and main frame.

35 75. In a stretching machine, a main frame, opposite bell-crank levers fulcrumed thereon, bars pivoted upon the levers, links connecting the levers and bars and furnishing therewith a supporting frame, opposite work-engaging jaws mounted upon the supporting frame, springs connecting the levers and main frame, and a jaw-operating member movable between the bars.

40 76. In a stretching machine, a main frame, opposite bell-crank levers fulcrumed thereon, bars pivoted upon the levers, links connecting the levers and bars and furnishing therewith a supporting frame, opposite work-engaging jaws mounted upon the supporting frame, springs connecting the levers and main frame, and a jaw-operating member movable between the bars and furnishing guides therefor.

45 77. In a stretching machine, a movable form, a plurality of members for gripping the material to be stretched, mechanism for successively operating the gripping members

and moving the form, and automatic means for stopping the operating mechanism after the operation of a portion of the gripping members and thereafter again stopping the operating mechanism before the form is 70 moved.

78. In a stretching machine, a movable form, work-gripping members associated therewith, operating mechanism for successively actuating the gripping members and 75 moving the form, driving mechanism which may be connected to the operating mechanism to effect both its gripping and form-moving operations, and means controlled by the operating mechanism for disconnecting 80 the driving mechanism and operating mechanism after the actuation of the gripping members.

79. In a stretching machine, a movable form, work-gripping members situated at 85 opposite sides of the form, operating mechanism for actuating the gripping members at one side of the form, actuating the opposite gripping members and moving the form, driving mechanism which may be connected 90 to the operating mechanism for both actuating the gripping members and moving the form, and means controlled by the operating mechanism for disconnecting the driving mechanism and operating mechanism after 95 each gripping operation.

80. In a stretching machine, a movable form, work-gripping members situated at opposite sides of the form, operating mechanism for actuating the gripping members at 100 one side of the form, actuating the opposite gripping members and moving the form, driving mechanism which may be connected to the operating mechanism for both actuating the gripping members and moving the 105 form, and means controlled by the operating mechanism for disconnecting the driving mechanism and operating mechanism after each gripping operation, said disconnecting means becoming ineffective after the operation 110 of both gripping means.

81. In a machine of the class described, work-engaging members, a reciprocatory head for moving said members, a source of power, connections including a clutch for 115 joining the head and source of power, a member actuated by the operator, connections between said member and the clutch to cause the engagement of the clutch upon actuation by the operator, and a member 120 movable with the head for disconnecting said clutch connections.

82. In a machine of the class described, work-engaging members, a reciprocatory head for moving said members, a source of 125 power, connections including a clutch for joining the head and source of power, a member actuated by the operator, connections between said member and the clutch to cause the engagement of the clutch upon 130

- actuation by the operator, and a member movable with the head for disconnecting said clutch connections, said connections being reestablished upon release of the operator-actuated member. 50
83. In a machine of the class described, work-engaging members, a reciprocatory head for moving said members, a source of power, connections including a clutch for joining the head and source of power, a member actuated by the operator, connections between said member and the clutch including a hook to cause the engagement of the clutch upon actuation by the operator, a disengaging member joined to the hook, and a member movable with the head for operating the disengaging member to withdraw the hook from its connection. 55
84. In a machine of the class described, work-engaging members, a reciprocatory head for moving said members, a source of power, connections including a clutch for joining the head and source of power, a member actuated by the operator, connections between said member and the clutch including a hook to cause the engagement of the clutch upon actuation by the operator, a disengaging member joined to the hook and being provided with a plurality of projections, and a member movable with the head for successive contact with the projections to effect a plurality of withdrawals of the hook from its connection. 60
85. In a machine for forming leggings, a form corresponding in contour to a portion of the leg, a mold for coöperation with the form, and means for stretching the legging-material upon the form. 70
86. In a machine for forming leggings, a form corresponding in contour to a portion of the leg, a mold for coöperation with the form, means at each side of the form for engaging the legging-material, and means for moving the form toward the mold. 75
87. In a machine for forming leggings, a form corresponding in contour to a portion of the leg, a mold coöperating with the form, means for yieldably supporting one of said coöperating elements, and means for stretching the legging-material upon the form. 80
88. In a machine for forming leggings, a form corresponding in contour to a portion of the leg, a mold for coöperation with the form, and automatic means to bring the form and mold successively into coöperation to act upon a single legging. 85
89. In a machine for forming leggings, a form corresponding in contour to a portion of the leg, a mold for coöperation with the form, means for heating one of these elements, and means for stretching the legging-material upon the form. 90
90. In a machine for forming leggings, a form corresponding in contour to a portion of the leg, heating means within the form, a mold for coöperation with the form, and means for stretching the legging-material upon the form. 95
91. In a forming machine, a form of different dimensions, and a plurality of heating means situated in different sized portions of the form and being of different heating capacity. 100
92. In a forming machine, a form of different dimensions, and a plurality of electrical heating means situated in different sized portions of the form and being of different heating capacity. 105
93. In a machine for forming leggings, a form having a calf portion and an adjacent contracted portion, and means for applying greater heat to the form at the calf than at the adjacent portion. 110
94. In a machine for forming leggings, a form having a calf portion and an adjacent contracted portion, and independent heating means situated in the two portions, that in the calf portion being of greater heating capacity. 115
- In testimony whereof we have signed our names to this specification. 120

JOHN B. HADAWAY.
THOMAS H. SEELEY.
